(57) **CLAIM**

The ornamental design for a barricade, as shown and described.

DESCRIPTION

FIG. 1 is a front view of a barricade according to the present design;

FIG. 2 is a rear view of the barricade of FIG. 1;

FIG. 3 is a bottom view of the barricade of FIG. 1;

FIG. 4 is a top view of the barricade of FIG. 1;

FIG. 5 is a right side view of the barricade of FIG. 1;

FIG. 6 is a left side view of the barricade of FIG. 1;

FIG. 7 is a top, right perspective view of the barricade of FIG. 1; and,

FIG. 8 is a front perspective view of the barricade of FIG. 1.

The broken line showing of FIGS. 1-8 is for the purpose of illustrating environmental structure and forms no part of the claimed design.
